UNITED STATES PATENT OFFICE

CHONG SUK PARK, DECEASED, LATE OF SACRAMENTO, CALIFORNIA, BY MONG Y. CHUNG,
ADMINISTRATOR, OF SACRAMENTO, CALIFORNIA

DESIGN FOR AN AUTOMOBILE SIGNAL CASING

Refiled for abandoned application, Serial No. 37,264, filed October 15, 1930. This application filed January 26, 1932. Serial No. 42,828. Term of patent 7 years.

To all whom it may concern:

Be it known that CHONG SUK PARK, deceased, last a native of Korea, and a subject of the Emperor of Japan, did invent a new, original, and ornamental Design for Automobile Signal Casing, of which the following is a specification, reference being had to the accompanying drawing, which is a perspective view of an automobile signal casing showing the new design.

This application is a renewal of the application of the said CHONG SUK PARK made in his lifetime and dated October 15, 1930, Serial No. D-37,264.

Claim:

The ornamental design for an automobile signal casing as shown.

MONG Y. CHUNG,
Administrator of the Estate of Chong Suk
Park, Deceased.
